(57) **CLAIM**

The ornamental design for a paddlefish fishing weight as shown and described.

DESCRIPTION

FIG. 1 is a front view of a paddlefish fishing weight showing my new design;

FIG. 2 is a rear view of the paddlefish fishing weight;

FIG. 3 is a left side view of the paddlefish fishing weight;

FIG. 4 is a right side view of the paddlefish fishing weight;

FIG. 5 is a top view of the paddlefish fishing weight;

FIG. 6 is a bottom view of the paddlefish fishing weight;

FIG. 7 is a top front side perspective view of the paddlefish fishing weight; and,

FIG. 8 is a bottom rear side perspective view of the paddlefish fishing weight.

The broken lines depict portions of a paddlefish fishing weight that form no part of the claimed design.
